CLAIM

I claim the ornamental design for a shoe, as shown and described.

DESCRIPTION

FIG. 1 is a front bottom perspective view shoe, showing my new design;

FIG. 2 is a rear bottom perspective view thereof;

FIG. 3 is a bottom view thereof;

FIG. 4 is a right side view thereof; and,

FIG. 5 is a front view thereof.

The broken lines depict features of the shoe that form no part of the claimed design.
